G. TOLLERUD

AUTOMOBILE OIL HEATING DEVICE

Filed March 15, 1927

INVENTOR.

Guy Tollerud,

BY

ATTORNEY.

Geo. F. Kimmel

UNITED STATES PATENT OFFICE.

GUY TOLLERUD, OF AUSTIN, MINNESOTA.

AUTOMOBILE OIL-HEATING DEVICE.

Application filed March 15, 1927. Serial No. 175,486.

The invention relates to an oil heater, and more particularly to the class of heaters for the crank cases or oil pans of internal combustion engines, used in automobiles or the like.

The primary object of the invention is the provision of a device of this character, wherein oil contained within a crank case, oil pan or the like employed in an internal combustion engine can be heated, from the exhaust of said engine, so that water, gasoline and kerosene contained in the oil introduced therein by suction from the intake manifold of the engine will be thrown off, so that the oil will be maintained at the required density for thorough lubrication and in this manner the longevity thereof is maintained at a maximum.

Another object of the invention is the provision of a heater of this character, wherein the construction thereof is novel in form, so that the same is readily adaptable for use in conjunction with the crank case, oil pan, or the like, of an internal combustion engine, without requiring any material alteration in the case, pan or the like, whereby exhaust from the engine can be utilized as the heating medium for oil contained within the case, pan or the like, to assure proper fluidity and refinement in the original quality of the oil for thorough lubrication in its use in the engine.

A further object of the invention is the provision of a heater of this character, wherein the exhaust from an internal combustion engine can be controlled for directing said exhaust through the heater or excluded therefrom at the option of an operator and when the exhaust is directed through the heater, it will heat the oil contained within a crank case, oil pan or the like of the engine to maintain the oil at a temperature for the attainment of the best lubricating results, the heater and its adjunct parts being of novel form, to render it adaptable for association with the conventional crank case, oil pan or the like, employed with internal combustion engines.

A still further object of the invention is the provision of a heater of this character, which is extremely simple in construction, thoroughly reliable and efficient both for heating and distilling oil within a crank case, oil pan or the like, readily and easily applied and removed, durable, and inexpensive to manufacture and install.

With these and other objects in view, the invention consists in the features of construction, combination and arrangement of parts, as will be hereinafter more fully described in detail, illustrated in the accompanying sheet, showing the preferred embodiment of the invention, and pointed out in the claims hereunto appended.

In the accompanying drawing:—

Figure 1 is a plan view of a crank case, oil pan or the like, of conventional type employed with internal combustion engines, showing the heater constructed in accordance with the invention associated therewith and connected to the exhaust manifold of the engine.

Figure 2 is a fragmentary vertical longitudinal sectional view through the crank case, oil pan or the like, and the heater in association therewith.

Figure 3 is a sectional view taken approximately on the line 3—3 of Figure 2 looking in the direction of the arrow.

Figure 4 is a fragmentary side elevation showing in detail valves controlling the exhaust in the exhaust manifold of the internal combustion engine.

Figure 5 is a fragmentary view in section.

Similar reference characters indicate corresponding parts throughout the several views in the drawing.

Referring to the drawing, in detail, A designates generally the crank case or oil containing lower section thereof in which is adapted to be placed the oil for lubricating the crank bearings of an internal combustion engine in the conventional manner. This case A has formed thereon the continuous marginal flange 10 through which at intervals are passed the usual bolt members 11 for the detachable securing of the crank case A to the engine body as is usual.

At one side of the case A as is customary there is arranged the exhaust manifold B, which is of any conventional or well known type. At a predetermined point within the exhaust manifold B is arranged a duplex valve structure C, provided with a cut-off valve 12 having its operating lever 13 exteriorly of said structure to be operated in any desirable manner, whereby the valve can be opened or closed at the option of the operator.

The heater constituting the present invention comprises an auxiliary case 14 of greater size than the case or section A to

accommodate the latter when telescoped over the same, the marginal portion of the case 14 being formed with an outturned continuous flange 15 adapted to match the flange 10 on the case A and through this flange 15 are passed the bolt members 11 for the securing of the cases A and 14 in place in their interfitted or assembled relation to each as is clearly shown in Figures 2 and 3 of the drawings.

In assembling the case 14 relative to the case A there is formed entirely about the bottom, sides and ends of said case A a heating chamber 16, while horizontally disposed within said case A at its point elevated from its bottom is a substantially U-shaped heating unit or pipe 17, the parallel legs 18 and 19 of which open through one side of the casing A and the leg 18 at its free end extends exteriorly for a distance of the casing A to provide a coupling 20 for a purpose presently described.

Mounted exteriorly on the case 14 on the side thereof opposite the location of the exhaust manifold B of the internal combustion engine is an outlet pipe 21 having its opposite ends opening through the side of the case 14 for communication with the chamber 16 between the latter and the case or section A, while medially of this pipe 21 is a downwardly directed exhaust or outlet nozzle 22 for the discharge of exhaust from the chamber 16, which exhaust is delivered thereto in a manner presently described.

Communicating with and leading from the valve structure C is a branch pipe or elbow 23 the latter opening into the case 14 and at this point of opening, the coupling 20 engages therein, so that the exhaust from the manifold B can be conveyed through the pipe or elbow 23 into the heating unit 17 through the leg 18, whence it will be conveyed through the leg 19 into the chamber 16 and therefrom through the pipe 21 and exhaust or outlet 22 as will be clearly obvious.

Arranged in the nipple 24 connecting the pipe or elbow 23 with the structure C is a suitable cut-off valve (not shown) adapted to be operated by the lever 25, which through the medium of the link 26 is connected with the lever or handle 13 of the valve 12, so that both valves can be actuated in unison, but on the opening of the valve in the nipple 24 the valve 12 will be simultaneously closed in the structure C. This valve 12 is located and arranged to close below the point of communication of the elbow or pipe 23 with the structure C, so that when the said valve 12 is closed the exhaust in the manifold B will be directed through the heater by pass-

ing through the pipe or elbow 23 into the heating unit 17 and chamber 16 between the cases A and 14, so that oil within the case A will be properly heated to assure fluidity thereto and to distill or eliminate water, gasoline and kerosene which have been drawn into the case A by suction in the intake manifold of the internal combustion engine. The spent exhaust for the heating of the oil in the case A is let off or discharged through the outlet 22 as will be clearly apparent.

On closing the valve in the nipple 24 the exhaust can be shut off from the heater and discharged from the exhaust manifold B to the atmosphere in the usual or customary manner as will be fully understood.

What is claimed is:

1. An oil heating attachment for motor vehicles comprising a pan adapted to be arranged in spaced relation and to completely surround the oil containing section of a crank case of an internal combustion engine and providing in connection therewith a heating chamber, a substantially U-shaped conveyor pipe located within said section and having one of its legs extending through one of the walls of said section and opening into said chamber and having the other of its legs extending through such wall and said chamber and through a wall of said pan, means for conveying exhaust from an engine directly to said last mentioned leg, and means connected to one of the walls of said pan for delivering the exhaust from said chamber.

2. An oil heating attachment for motor vehicles comprising a pan adapted to be arranged in spaced relation and to completely surround the oil containing section of a crank case of an internal combustion engine and providing in connection therewith a heating chamber, a substantially U-shaped conveyor pipe located within said section and having one of its legs extending through one of the walls of said section and opening into said chamber and having the other of its legs extending through such wall and said chamber and through a wall of said pan, means for conveying exhaust from an engine directly to said last mentioned leg, and means connected to one of the walls of said pan for delivering the exhaust from said chamber, and said means for delivering the exhaust from said chamber communicating at two points with the latter and having a single outlet.

In testimony whereof, I affix my signature hereto.

GUY TOLLERUD.
